UNITED STATES PATENT OFFICE.

ALVIN TAPLIN, OF FORESTVILLE, CONNECTICUT.

SCRUBBING-MACHINE FOR REMOVING FOREIGN MATTER FROM THE SURFACES OF GLOBULAR OBJECTS.

No. 812,466.

Specification of Letters Patent.

Patented Feb. 13, 1906.

Application filed August 22, 1904. Serial No. 221,762.

To all whom it may concern:

Be it known that I, ALVIN TAPLIN, a citizen of the United States, residing at Forestville, in the county of Hartford and State of Connecticut, have invented certain new and useful Improvements in Scrubbing-Machines for Removing Foreign Matter from the Surfaces of Globular Objects, of which the following is a specification.

10 My invention relates to improvements in scrubbing - machines for removing foreign matter from the surface of globular objects; and the main object of my improvement is simplicity of construction and efficiency in 15 operation.

In the accompanying drawings, Figure 1 is a broken plan view of my machine. Fig. 2 is a broken longitudinal section of the same on the line *x x* of Fig. 1 with parts in side elevation. Fig. 3 is a transverse section of the said 20 machine on the line *y y* of Fig. 1.

A designates a tub or liquid-tight vessel or trough, which in the specific form shown also constitutes the frame of the machine and upon 25 which a brushing or scrubbing roller B is mounted to revolve in suitable bearings on the shaft 4. I prefer to provide one end of this shaft with a balance-wheel 5, which may in turn be provided with a suitable handle 6 30 for turning the shaft and roller by hand. The opposite end of the said shaft may also be provided with a short crank 7 for the application of a connecting-bar 8 and a foot-treadle 9 for driving the roller by foot-power. If desired, 35 a power - driven belt may be applied to the balance-wheel 5.

The upper surface of the scrubbing-roller B should be slightly inclined in the longitudinal direction of the machine, and I prefer to get 40 the incline, pitch, or slant by the combination of a tapering roller with an inclined axis for said roller and to mount the said roller on the trough or frame with its under face in a horizontal or level position, so that both ends 45 of the roller will dip into the water or other scrubbing fluid to the same depth. In this way the slant or pitch of the upper surface of the roller is twice as great as it would be with a roller of the same taper set on a horizontal 50 axis, while the incline of the shaft or axis is only half what it would be to give the upper surface of a cylinder the same pitch or slant. A suitable incline for the top of the roller when the machine is used for scrubbing oranges or 55 grape-fruit may be had by using a roller ten feet long and twelve inches in diameter at one

end and eight inches at the other end, provided the shaft or axis is set so as to bring the under face of the roller level.

By the side of the roller B, I arrange a scrubbing-apron C, with its lower edge on an incline corresponding with that of the roller and approaching the said roller below its summit, whereby an inclined trough or chute is formed by the combined faces of the said roller and apron. This apron and scrubbing-roller are covered with any suitable filamentous brush-like material 10 on any suitable body. A matting of cocoanut fiber similar to an ordinary foot - mat furnishes a good scrubbing- 60 surface and may be secured upon a wooden roller and a board to form, respectively, the scrubbing-roller and apron. Mounted on the frame at the large end of the roller is a feeding trough or chute 11 of substantially a V- 70 shaped form in transverse section, with its oppositely-inclined side walls extended on a horizontal incline to any desired length for supporting in single file the objects to be scrubbed and forcibly directing them into the 75 trough or chute formed by the combined roller and apron. The feeding-chute is inclined in the same direction, but on a steeper incline than the top of the scrubbing-roller. A delivery-passage 12 is formed in the machine at 80 the discharge end of the scrubbing-roller and apron.

The machine may be used for scrubbing foreign matter from the surface of any globular-shaped objects—as, for example, fruit and 90 vegetables or other objects of a more or less spherical form. The pitch or incline of the scrubbing-roller may vary according to the variation from a true sphere that the objects have. As shown, it is at the proper pitch for 95 scrubbing grape-fruit and oranges, which are more nearly round than some other fruits. Water or other scrubbing fluid is placed in the tank in sufficient quantity to cover the under face of the scrubbing-roller. The roller 100 is driven in the direction indicated by the curved arrow in Fig. 3. The fruit is fed into the machine through the feeding-chute 11 and on striking the roller and apron is rolled over and over against the scrubbing-surfaces 105 of the said brush in connection with the water taken up by the roller, and passing longitudinally of the roller and apron by the combined action of gravity and the rotary movement of the scrubbing-roller to the delivery 110 12 the fruit is scrubbed when wet, and its surface is thoroughly cleaned of all foreign mat-

ter without cutting, crushing, peeling, bruising, or otherwise injuring the fruit or in any way removing any natural part thereof. The broken-line circles in Fig. 1 indicate the fruit 5 in its passage through the machine. It should pass along slowly, and the machine may be kept substantially full from end to end of the roller. The horizontally-extended brushing- 10 roller and apron, which form the scrubbing-chute, are inclined at a slight angle, so as to feed the fruit therethrough in time by gravity, aided by the rotary roller, while the incline is so flat as to serve as a resistance to the rolling of the fruit through the scrubbing-chute by 15 gravity alone, whereby the said resisting-incline may retain the fruit in the scrubbing-chute long enough to be thoroughly scrubbed. The incline of the feeding-chute, as before stated, is greater than that of the top of the 20 roller, and it is steep enough to overcome the resistance to the rolling movement of the fruit that may be caused by its flattened or non-spherical shape and the friction that may be caused by the oranges pressing against each 25 other, so that said chute acts as a forcing-incline to force the fruit down through the chute

by gravity alone when the fruit is retarded in the brushes to enable the hopper to be loaded. With such a forcing-incline when the feeding-chute 11 is loaded the weight of the fruit 30 therein assists in carrying the fruit along the length of the roller. If the feeding-chute is of considerable length, the passage of the fruit along the scrubbing-roller may be made faster or slower by varying the quantity of fruit in 35 the feeding-chute. The longer the time that the fruit is retained in the machine, everything else being equal, the more it will be scrubbed.

I claim as my invention—

The combination of a frame with a tapering scrubbing-roller mounted on the said frame with its axis on an incline and with its under face level, a liquid-tight vessel or trough into which the under face of the said scrubbing-roller extends, and a scrubbing-apron 45 arranged by the side of the said roller below the summit thereof substantially as described.

ALVIN TAPLIN.
